United States Patent Office.

ALBERT J. REDWAY, OF CINCINNATI, OHIO, ASSIGNOR TO REDWAY AND BURTON, OF THE SAME PLACE.

Design No. 2,718, dated August 6, 1867.

DESIGN FOR A CHARCOAL-STOVE.

The Schedule referred to in these Letters Patent and making part of the same.

TO ALL WHOM IT MAY CONCERN:

Be it known that I, ALBERT J. REDWAY, of Cincinnati, in the county of Hamilton, and State of Ohio, have invented a new Design for a Charcoal-Stove, which design is represented in the accompanying illustration, which forms a part of this specification.

I claim and desire to secure by Letters Patent—

The design for a charcoal-stove, substantially as represented in the accompanying illustration.

In testimony of which invention I hereunto set my hand.

Witnesses:

GEO. H. KNIGHT,

JAMES H. LAYMAN.
